LOCK MECHANISM

Almos Fred Terenyi and Arpad Terenyi,
Dearborn, Mich.

Application May 2, 1935, Serial No. 19,432

18 Claims. (Cl. 70—29)

Our invention relates to improvements in lock mechanisms for doors of bodies of automotive vehicles actuated by means of manually operated handle members, and the objects of our invention are, first, to provide a lock mechanism having a handle operating mechanism adapted to be disengaged from the remainder of the locking mechanism to enable the handle member to be revolvably operated without further operation of the locking mechanism; second, to provide a locking mechanism having an operating handle which is adapted to be operatively disengaged by a key operated lock mechanism from the outside of the body of the automotive vehicle so that the operating handle member may be completely revolved without operating the remainder of the locking mechanism; third, to provide a lock mechanism having an operating handle member adapted to be manually operated by suitable means located within the body of the vehicle and adapted to disengage the operating handle member from the rest of the locking mechanisms so that the operating handle may be completely revolved without operating the remainder of the lock mechanism; fourth, to provide a lock mechanism for a door of a vehicle with means for disengaging the lock mechanism for its operating handle and at the same time locking the remaining portions of the lock mechanism against movement; fifth, to provide a lock mechanism having a handle member adapted to be freely engaged relative to the rest of the lock mechanism with indexing mechanism for positioning the handle member in a plurality of indexed positions; sixth, to provide a lock mechanism for a door and having a handle adapted to freely rotate relative to the rest of the lock mechanism with a pair of resiliently actuated indexing members to insure the positioning of the handle in predetermined indexed positions when the door is operating to its fully closed position; seventh, to provide a lock mechanism for a door and having an embossed portion in its edge portion for receiving therein a cam portion of a freely rotating dog member connected with an operating handle; eighth, to provide a lock mechanism having a dog member mounted on a shaft member provided with a pair of cylindrical washers revolvably engaging wall portions of the housing of the lock mechanism to provide a bearing for the dog member; and ninth, to provide a lock mechanism having a fixed index member engaging a resiliently actuated and revolvably mounted dog member for operating portions of the lock mechanism to a

disengaged position relative to and to permit free rotation of a revolvably mounted roll-back member.

We attain these objects by the mechanism illustrated in the accompanying drawings, in which:—

Figure 1 is a horizontal sectional view of a door of a body of an automotive vehicle equipped with our lock mechanism, said sectional view disclosing in a general way the installation of our lock mechanism therewith; Fig. 2, a horizontal sectional view of a portion of the door mechanism disclosed in Fig. 1, together with a partial horizontal sectional view of the door post or frame with which the door is associated, said Fig. 2 being drawn to a larger scale than that of the door and lock mechanism disclosed in Fig. 1, said Fig. 2 disclosing in a general way the installation of our lock mechanism in a door associated with a door post or frame; Fig. 3, a vertical section of the door lock mechanism with its outer plate or housing removed to more fully disclose various parts of the lock mechanism, said lock mechanism being disclosed in an operative position in which its plunger or catch mechanism is located in its retaining position to maintain a door in a locked position, or in other words, with the lock mechanism in a position at the beginning of its operating movement preparatory to operating the lock mechanism to unlock the door of the vehicle; Fig. 4, a view similar to Fig. 3 and disclosing the various parts of the lock mechanism with its outer plate or housing member removed and with the various parts of its operating mechanism disclosed in their operative positions at the end of their operating movement after the lock mechanism has been operated to a position at the end of its operating movement for unlocking the door, said Fig. 4 further disclosing a sectional view of the door frame or post mechanism in association with the lock mechanism; Fig. 5, a view of the lock mechanism similar to that of Figs. 3 and 4 but with the various parts of the lock mechanism disclosed in their operative positions and in which said various parts of the lock mechanism have been actuated as by a handle mechanism within the door or by a key and lock mechanism from the outside of the door to position the operating handle and its roll-back mechanism in complete disengagement from the remaining locking mechanism and to maintain the operating handle in an unlocking position, said Fig. 5, however, not disclosing any portion of the door post or frame construction; Fig. 6, an end view of

the lock mechanism as disclosed in Fig. 3; Fig. 7, a partial sectional view of the door of the automotive vehicle together with our locking mechanism installed therein and viewed from the inside of a door, together with manually operating means remotely located from the lock mechanism and on the inside of the door for operating the lock mechanism, said view disclosing a portion of the door of the post or frame construction, said Fig. 7 not disclosing any plate member covering the inside of the lock mechanism B at the inside of the door assembly A; Fig. 8, a sectional view of the locking mechanism in the door of a vehicle, said view being taken on the line 8—8, Fig. 3, said Fig. 8 disclosing the key as having been removed from the key lock mechanism which is diagrammatically indicated in Fig. 8; Fig. 9, a sectional view through the lock mechanism and taken on the line 9—9, Fig. 3; Fig. 10, a sectional view through the lock mechanism, on the line 10—10, Fig. 3; Fig. 11, a partial sectional view of the lock mechanism and taken on the line 11—11, Fig. 3; Fig. 12, a partial sectional view more clearly disclosing an additional spring mechanism for maintaining the operating handle in predetermined positions irrespective of engagement with the remainder of the lock mechanism; Fig. 13, a side view of one of the rivets or studs for connecting the dog member operated by the key lock mechanism with the operating members of the lock mechanism; Fig. 14, an end view of the rivet or stud member disclosed in Fig. 13; Fig. 15, a side view of one of the washer members for supporting the operating shaft of the key lock mechanism; Fig. 16, an end view of the washer member disclosed in Fig. 15; Fig. 17, a side view of the dog member which is operated by the key lock mechanism of the lock mechanism; Fig. 18, an end view of the dog member disclosed in Fig. 17; Fig. 19, an end view of the roll-back member operated by the outside handle of the lock mechanism; Fig. 20, a side view of the roll-back member disclosed in Fig. 19; Fig. 21, a side view of one of the index members engaged by the dog member disclosed in Figs. 17 and 18; Fig. 22, a sectional view of the index member disclosed in Fig. 21 and taken on the line 22—22, Fig. 21; Fig. 23, a view taken on the line 23—23, Fig. 2 and disclosing a partial side view of the door post or frame mechanism assembly C, to more fully disclose the recess 27 which extends for a portion only of the distance across the transverse section of the door post or frame mechanism C and is adapted to receive and contain the end of the lock plunger 28; Fig. 24, a partial side view of the door assembly and disclosing a view of the key lock mechanism from the outside of the door assembly and without the key associated therewith; Fig. 25, a partial longitudinal view of the key lock mechanism and the spindle 89 together with the lost motion mechanism connected therebetween, and Fig. 26, a sectional view of the key and its lost motion mechanism, said sectional view being taken on the line 26—26, Fig. 25.

Similar numerals refer to similar parts throughout the several views.

The various parts of the lock mechanism assembly B are mounted as more fully disclosed hereinafter between the inner plate or housing 1 which is mounted on the inner side of the door assembly A relative to the interior of the body of the vehicle and the outer plate or housing member 2 which is mounted at the outside

of the lock mechanism assembly B and thus in an interior of the door assembly A but in an outer position relative to the plate or housing member 1 as referred to the interior of the body of the vehicle, the inner and outer plates 1 and 2 forming a box like construction having the chamber 3 therein for containing the various parts of the lock mechanism. 5

The door assembly A as disclosed in Fig. 1 is disclosed with conventional construction generally and in which the outer wall portion or housing member 4 is provided with the flange or ledge portion 5 at the hinge portion of the door assembly A, said hinge portion of the door assembly A being located conventionally in many automotive vehicles at the forward portion of the door assemblies of the automotive vehicle, the door assembly A being further provided with the flange or ledge portion 6 which is located at the outermost swinging end of the door assembly A and thus rearwardly of the hinge portion of the door in many automotive vehicles, the flange or ledge portion 6 being adapted to contact the flange or ledge portion 7 of the door post or frame assembly C as disclosed in Fig. 2. 25

The outer member 4 is further formed with the flange or ledge portion 8 which is adapted to contact and engage the conventional catch member 9 which is mounted on the door post or frame assembly C by the screws 10 or similar suitable means, the catch member 9 being suitably mounted in the door post or frame assembly C so that the flange or ledge portion 8 of the door assembly A will have a ledge on the door post or frame assembly C for substantially the full height of the door assembly A. The door assembly A is further provided with the inner member 11 which forms the inner wall portion of the door assembly A and may be suitably connected to the flange portion 12 which may be formed as an extension of the flange or ledge portion 8 and may be suitably connected to said flange portion 12 and to the flange portion 13 at the hinged end of the door assembly A as by welding or similar means. The wall portion 11 will be suitably formed with the offset portion 14 to provide the recess 15 which is adapted to receive and contain the lock assembly B, the lock assembly being suitably retained in a transverse direction by the plate 16 which forms an inside wall portion of the recess 5 and which may be secured by the screws 17 to the member 11, the lock assembly B being retained in a horizontal plane in one direction by engagement with the flange portion 14 of the member 11, and if desired, in a horizontal direction in two directions by engagement with the screws 18 and the plate member 16 and which may extend through the plate member 16, as disclosed in Fig. 8, and through the plates 1 and 2 of the lock assembly B to threadably engage the offset portion 14 of the member 11, said plates 1 and 2 being provided with suitable openings 18A, or if it is desired to dispense with the use of the plate 16, the screws 18 may extend through the plates 1 and 2 only to engage the offset portion or wall 14. 55 60 65

It is to be noted that various means may be disclosed for mounting and securing the lock assembly B within the door assembly A and conventional means is herewith disclosed, it being understood that other and suitable means such as rivets may be used in place of the screws 18 if desired. 70

The offset portion 14 may be provided with the suitable holes or openings 19 and if the plate 16 75

is used, said plate may be provided with similar holes or openings 20 as disclosed in Fig. 8, said holes 19 and 20 being utilized for receiving the offset portions 21 of the plate 1 and the offset portions 22 of the plate 2 of the lock assembly B to further position the lock assembly B and secure it in its mounted position in the recess 15 of the door assembly A.

The plate 2 may be provided with the flange portion 23 at one of the ends to extend adjacent the plate 1 and to form a closed end of the chamber 3. Also the plate 2 may be extended at its other or exposed end to provide the flange 24 which may extend across and contact the outer surface of the flange portion 25 which may be formed on the plate 1, the flange portion 24 extending for substantially the full width of the lock assembly B. The flange portions 24 and 25 may be further secured together by the screw members 26 which extend through the flange portions 24 and 25 of the plate members 2 and 1.

The locking plunger 28 is provided with the curved or beveled surface 30 which is adapted to strike and engage the inclined surfaces 31 and 32 of the catch member 9 when the door assembly A is pivotally moved or slammed to its closed position as disclosed in Fig. 2 and in which the lock plunger 28 finally comes to rest in a position in engagement against the inner surface of the main lock retaining surface 33 of the catch member 9, the locking plunger 28 extending through the openings 29 of the flange portions 24 and 25 of the plate members 2 and 1.

A plate 38 is provided with the arm 54 which is provided with the flange portion 55 which extends substantially at right angles to the main body portion of the plate 38 and is normally positioned adjacent the inside surface of the flange portion 25 of the plate 1. The roll-back member 49 is provided with the polygonal shaped opening 56 extending therethrough, said polygonal opening 56 being disclosed as being of rectangular shape, although it may be provided with any desired number of polygonal sides, said polygonal shaped opening 56 being adapted to receive the shaft 57 therethrough, said shaft 57 having a polygonal shape suitable for being fitted within and being secured in the polygonal shaped opening 56 of the roll-back member 49. The shaft member 57 also extends through and is secured in the polygonal shaped openings 56 of the roll-back member 49, the roll-back member 49 being provided with cylindrical portions 49A at each of its ends and which are revolvably mounted in the holes or openings 60 which extend through the offset portions 21 and 22 of the plates 1 and 2, said roll-back member 49 being further provided with the cylindrical surfaces 49B which are revolvably mounted in the cylindrical recesses 63 and 64 which are respectively formed in the plate members 1 and 2, one of the cylindrical surfaces being interrupted by the formation of the flattened surfaces 48 but leaving sufficient cylindrical surfaces between the flattened surfaces 48, in conjunction with the full cylindrical surfaces 49B at the other end of the roll-back member 49 and with the cylindrical surface 49A to form an adequate bearing in the openings or recesses 60, 63 and 64 of the plates 1 and 2.

The roll-back member 49 is provided with the cam member 65 which is provided with the surface 66 which normally extends adjacent the cam surface 67 of the arm 68 of the dog member 36, the surface 66 and 67 being normally separated

by the slight or small space 69 as disclosed in Fig. 3 to insure that the surface 47 of the plate member 38 will always be urged by the resilient member 52 to a contactual engagement with one of the surfaces 48 of the roll-back member 49 and to thus position said surface 66 with clearance relative to said surface 67, the cam member 65 of the roll-back member 49 being provided with the curved surface 70 so positioned to provide the cam or roll back member 65 with sufficient stock 10 or cross section to insure rigidity for the necessary strength to withstand the loads encountered in operation.

The dog member 36 may have its arm 35 provided with a lesser thickness than the remainder 15 of the dog member 36 to provide the arm 68 with sufficient thickness to provide the surface 67 with such area as to properly withstand the contactual and thrust engagement of the surface 66 of the roll-back member 49 therewith. The line 71 of 20 the dog member 36 indicates the division line between the different thicknesses of the dog member 36.

The shaft member 57 is of sufficient length to extend through the member 72 which acts as a 25 reinforcing member and which is suitably secured between the inner wall portions 14 of the recess 15 and the outer wall portion of the housing member 4 of the door assembly A, said member 72 being located in abutment with the flange portion 12 30 and having its inner flange in abutment with the inner wall portion 14 of the recess 15 as disclosed in Fig. 1, said shaft 57 together with the portion 77 further extending through the outer wall portion of the housing member 4 of the door assembly 35 A and through the plate member 73 which is secured by the screws 74 to the wall portion of the housing member 4 of the door assembly A and is provided with suitable openings through which the key 75 may be inserted into the key lock 40 mechanism assembly 76, as disclosed in Fig. 8, the key 75 being disclosed in a removed position from and relative to the key lock mechanism assembly which is indicated by the dotted lines 76 in Fig. 8, the plate 73 thus providing the opening for the 45 insertion of the key 75 and enhancing the appearance of the door assembly A. The shaft 57 extends through the wall portions of the door assembly A and is suitably connected to the extension portion 77 of the handle member 78 which is 50 provided with the handle portion 79 together with the angular shaped portion 80 at the opposite end of the handle member 78 to provide ornamental characteristics for the handle member 78, said handle member 78 disclosed in the full lines 55 and substantially as mounted at the outer ends of the shafts 57 in Figs. 4 and 3, to disclose the portions of the handle member 78 relative to the various positions of the roll-back member 49.

The extension portion 77 is secured to the shaft 60 member 57 and is of sufficient length to provide a suitable space between the inner side of the handle member 78 and the outside surface of the wall portion of the housing member 4 of the door assembly A to enable the hand of the operator to 65 grasp the handle portion 79 without interference with the housing member 4 of the door assembly A.

The resilient member 81 is provided with the coil portion 82, which is suitably anchored by the 70 screw, stud or rivet 83 adjacent the inside surface of the plate member 1, and is provided with the straight portion 84 adapted to engage the surfaces 48 of the roll-back member 49 to position and index the shaft member 57 together with the 75

handle member 78 in its plurality of indexed portions, the various indexed positions of the cam portion 65 of the roll-back member 49 being indicated by the dotted line 65A in Fig. 5 thus preventing the handle member 78 together with the roll-back member 49 from swinging to and fro in an unrestrained manner when the door assembly A is slammed to its closed position and during which operation the surface 47 of the plate 44 may be forced to a position of disengagement relative to the surfaces 48 of the roll-back member 49, thus insuring that the handle member 78 will always be in one of the four indexed positions at all times as viewed from the outside of the door assembly A, the resilient member 81 being further provided with the extension portion 85 which is provided with the curved end 86 which is adapted to engage the inside surface of the flange portion 25, thus causing the resilient member 81 to always exert a thrust against one of the surfaces 48 of the roll-back member 49.

The dog member 87 is provided with the polygonal shaped opening 88 which is disclosed as being of rectangular shape suitable for receiving and providing a driving means between the dog member 87 and the shaft member 89 which is suitably secured in the polygonal shaped opening 88.

The dog member 87 is further provided with the extension portion 90 which is provided with the hole 91 which is adapted to enclose a rivet and be secured by riveting, as at 92A, to the cylindrical portion 92 of the stud 93 which is slidably mounted in the boss 94 of the connecting member 95, the connecting member 95 being preferably constructed of relatively thin stock, a portion of which may be displaced to form the boss portion 94 provided with a countersunk recess for receiving the tapered head portion 96 of the stud member 93, the dog member 87, together with the stud member 93, being adapted to slidably move in the bore of the boss portion 94 to permit the index portions 97 of the dog member 87 to engage and disengage relative to the index grooves 98 of the index member 99 which is suitably secured to the inside surface of the plate 1 of the lock assembly B as by welding, soldering or similar means, the index member 99 being provided with the hole or opening 100 extending therethrough to allow the shaft member 89 to extend therethrough with operating clearance therearound.

The resilient or spring member 101 is mounted to extend around the shaft member 89 and to engage and extend between the inner surface of the plate member 2 and the inside surface of the dog member 87 to continually exert a thrust against the dog member 87 and to cause the index portions 97 of the dog member 87 to engage the index grooves 98 of the index member 99, the dog member 87 thus being adapted to slidably move against the pressure of the spring 101 and to allow the dog member 87, together with the stud member 93 to slide in the bore of the boss portion 94 to further allow the index portions 97 of the dog member 87 to slide or move out of engagement with the index grooves 98 of the index member 99 when the shaft 89 is revolved by means of the handle member 102 having the handle portion 103, said revolvable movement of the shaft member 89 actuating the connecting member 95 as more fully disclosed hereinafter.

The shaft member 89 extends through and is suitably secured, as by a press fit in the polygonal openings 58 of a pair of the washer members 59

which are mounted in the offset portions 21 and 22 of the plates 1 and 2, the pair of the washer members 59 being each provided with the cylindrical portion 61, Fig. 15, which are revolvably mounted in the holes or openings 60 which extend through the offset portions 21 and 22 of the plates 1 and 2, said washer members 59 each being further provided with the cylindrical surfaces 62 which are revolvably mounted in the cylindrical recesses 63 and 64 which are respectively formed in the plate members 1 and 2.

The shaft 89 also extends through a suitable opening in the plate 1 and is secured to the hub 104 of the handle member 102 by the screw or rivet 105 on the inside of the door assembly A and within the interior of the body of the vehicle.

It is also to be noted that the shaft 89 will extend through the plate 2 of the lock mechanism B and will be operatively connected with the key lock mechanism 76 which is diagrammatically indicated in Fig. 8 as this is of conventional construction and adapted to receive and be operated by the key 75 which is disclosed in a position removed from the key lock mechanism 76, the key lock mechanism 76 being suitably mounted in the reinforcing member 72 or is suitably supported by the wall portion of the housing member 4 of the door assembly A. The connecting member 95 is provided with the curved surface or recess 106 to provide operating clearance relative to the roll-back member 49, the connecting member 95 being further provided with the curved surface or recess 107 to provide operating clearance around and relative to the spring 101 and the shaft member 89, the connecting member 95 being pivotally connected to the arm 63 of the dog member 36 by the rivet or screw 108 which may have a head portion similar to the head portion 96 of the stud 93 for assembly in the boss portion 109 which may be formed by displacing a portion of the connecting member 95 similar to the formation of the boss portion 94.

The connecting member 95 may be provided with the rib portion 110 which may extend substantially longitudinally thereof and be formed by displacing a portion of the metal of the connecting member 95 to reinforce the connecting member 95. It is also to be noted that the plate 38 will be provided with the offset portion 111 which enables the upper portion of the plate member 38 to be positioned adjacent the inner side of the coils of the resilient member 52 while the lower portion of the plate member 38 is thereby positioned in slidable engagement with and adjacent the inner surface of the plate 1 of the lock assembly B.

The lock plunger 28 is provided with the plate portion 32 at its inner end having a thickness substantially less than the thickness of its portion 32 being formed by machining away a portion of the stock of the lock plunger to form the boss 33 having the slot 34 extending between said boss 33 and the plate portion 32 for receiving the arm 35 of the dog member 36 which is pivotally mounted on the rivet or shaft member 37 which is mounted in the boss 33 and the plate portion 32 and extends through the slot 34.

The plate 38 is secured to the plate portion 32 of the lock plunger 28 by the four rivets 39, the plate 38 being provided with the extension portion 44 having the slot 40 which slidably engages and supports the plate 38 on the rivet or stud 41 secured as by riveting, in the plate 1 of the lock

assembly B, the head 42 of the rivet 41 retaining the plate 38 on the shouldered portion 43 in its slideable movement.

It is to be noted that the engagement of the rivet 41 with the slot 40 together with the upper edge surface of the plate portion 32 of the locking plunger 28, to which the plate 38 is riveted, with the plate or bracket 45, will stabilize and guide the plate 38 together with the locking plunger 28 in their slidable movement, the bracket 45 being rigidly secured as by welding or other similar or suitable means, to the inside surface of the plate 1, said bracket 45 being provided with the flange portion 46 for engaging said edge portion of said plate portion 32.

15 plate portion 32. The plate 38 is provided with the surface 47 which is always urged by the resilient or spring member 52 to engage one of the flattened or indexing surfaces 48 of the roll-back member 49 20 which is disclosed as being provided with four of said indexing surfaces 48 being provided as desired, said resilient member 52 being formed with spiral coils of rectangular cross section and with one of its ends 50 secured in the boss 51 25 which may be formed by displacing portions of the plate 1, or if desired, a stud or similar member may be suitably anchored in the plate 1 and to which the end 50 of the resilient member may be secured, the other end 53 of the resilient 30 member 52 being formed as an extension portion having a curved end to position the end 53 in engagement with the inner end of the plate portion 32 and retained in a transverse direction by being positioned between the side surfaces 35 of the plate 38 and the plate 1.

35 of the plate 38 and the plate 4. The dog member 87 is provided with the extension portion 133 which is provided with the surface 132 adapted to engage the flange portion 55 of the plate 38 and retain and prevent the plate 38 from being actuated in its slidable movement by its operating mechanisms when the dog member 87 has been rotated or turned to the position as disclosed in Fig. 5 thus constituting a lock means for preventing the actuation of the lock plunger 28, the plunger 28 together with the plate 38 being adapted for actuation by the handle 102 or the handle member 120, the actuation of the plunger 28 and the plate 38 by said handle 102 or handle member 120 revolving the dog member 87 from its position as disclosed in Fig. 5 to its position as disclosed in Fig. 4, the shaft 89 being conventionally connected with the key lock mechanism 76 by lost motion mechanism, thus permitting the shaft 55 89 together with the mechanism connecting the shaft 89 with the key lock mechanism 76, to revolve through a partial revolution without disturbing the key 75, and to permit the dog member 87 to be partially revolved to the position disclosed in Fig. 4 where it does not engage the flange 55 of the plate 38.

It is to be noted that the flange portion 55 of the plate 38 will slidably contact the edge surface of the dog member 87 as the plate 38 is slidably operated, said dog member 87 being retained against movement by the engagement of its index portions 97 with the grooves 98 of the fixed index member 99 during the slidable operation of the plate 38, the upper edge surface of the index member 99 being positioned with an operating clearance space relative to the flange portion 55 of the plate 38.

The rod or link member 112 is slidably connected with the plate 39 by means of the rivet 75 113 slidably engaging the sides of the slot 114

which is provided in the plate 38, said rivet 113 being suitably secured in the rod member 112 and having the head 115 for retaining the plate 38 thereon, the rod member 112 being suitably provided with the teeth 116 or ratchet construction for engaging similar teeth or ratchet construction suitably provided on the shaft member 117 suitably mounted in the bracket member 118, which is secured to the inside of the door assembly A by the screws, rivets or similar fastening members 119, as disclosed in Fig. 7, the rod member 112 extending through the bracket member 118 and thus being adapted to be actuated by the handle member 120 connected with the shaft member 117 to actuate the plate 38 together with the plunger 28 inwardly relative to the outermost swinging edge portion of the door assembly A to disengage the plunger 28 from engagement with the catch member 9, thus permitting the door assembly A to be unlocked and opened from the interior of the body of the vehicle, the bracket 118 together with the handle 120 and shaft members 117 being adapted for location at a remote position from the lock assembly B and on the inside of the door assembly A, the engagement of the rivet 113 with the slot 114 permitting the plate 38 to slidably move past and overrun the rivet 113 and the rod member 112 to enable the mechanism of the lock assembly B to be operated by the handle member 128 or by the handle member 102 or the key 175 without operation of the rod member, the overrun position of the plate 38 relative to the rod member 112 being disclosed in Fig. 4, the plate 38 being further disclosed in Fig. 7 as having been moved from its normal position, indicated by the dotted lines 121, to the position as shown by the full lines.

shown by the full lines. It is to be noted that the flange portion 25 of the plate 1 is provided with the opening or 40 aperture 122 through which the cam portion 65 of the roll-back member 49 will extend and re- 45 move when the roll-back member is revolvably operated by the handle member 78 and in order to maintain a closed end of the chamber 3 of the lock assembly B and to prevent the roll-back member 49 from being observable when the door assembly A is in an opened position, the flange portion 24 is provided with the expanded or embossed portion 123 which is located sub- 50 stantially concentrically with the axis of the roll-back member 49.

It is also to be noted that the door post or frame assembly C will be located with a slight clearance space 124 between it and the edge surface of the outermost edge portion of the door assembly A which will also extend between the outer surface of the embossed surface 124 and the recess 27 which is formed in the wall portion of the door post or frame assembly A with a shape similar to the embossed portion 123, the recess 27 extending from the outer surface of the door post or frame assembly C which is engaged by the flange portion 8 to substantially the line 125 which thus leaves the portion 126 of the door post or frame assembly C for closing the rear side of the recess 27 into which extends the embossed portion 123. 55 60 65

The door assembly A is disclosed in Figs. 1 and 8 as being equipped with the felt, cardboard or similar member 127 which extends across the inside surface of the wall portion of the housing member 11 and the plate 16, where such a plate is used, together with the fabric or upholstery member 128 suitably secured to the cardboard 75

member 127 and provided with the bead portion 129 and the pocket member 130.

In operation and with the door assembly A in its normally closed and unlocked position, as disclosed in Fig. 3, the movement of the handle member 78 in a clockwise direction will rotate the roll-back member 49 which will cause the cam portion 65 to engage the surface 67 of the arm 68 of the dog member 36 which will move the plate 38 together with the lock plunger 28 to the positions disclosed in Fig. 4 in which the end of the plunger 28 is withdrawn from engagement with the surface 33 of the catch member 9 to the position 131, Fig. 4, which allows the door assembly A to be pivotally moved to an open position as desired, the connecting member 95 pivotally moving relative to the dog members 87 and 36.

When it is desired, with the door assembly A in a closed position as disclosed in Fig. 3, to lock the door assembly A, the operator may insert the key 75 in the key lock mechanism 76 and by turning the key 75, the mechanism of the key lock mechanism 76 which is operatively connected with the shaft member 89 will rotate the shaft member 89 together with the dog member 87 which will move the surface 132 of the extension portion 133 of the dog member 87 to an engaged position with and relative to the flange portion 55 of the plate 38, as disclosed in Fig. 5, and which also causes the connecting member 95 and the dog member 36 to assume the positions disclosed in Fig. 5, and in which positions the cam portion 65 of the roll-back member 49 cannot engage the surface 67 of the dog member 36 and therefore the lock mechanism B cannot be operated, the operation of the handle member 78 merely rotating the roll-back member 49 which will be positioned when at rest in indexed positions due to the engagement of the flat portions 84 of the spring 81 engaging the flat-tened surfaces 48 of the roll-back member 49, the cam portion 65 of the roll-back member 49 being indicated in its indexed positions by the dotted lines 65A, Fig. 5. Also the dog member 87 is adapted to disconnect the outer handle 79 and its roll-back 49 from the plunger 28 by raising the talon 36 out of the path of the roll-back 49 as the dog member is operated to a locking position, as disclosed in Fig. 5, relative to the outer handle 79 and roll-back 49.

The lost motion mechanism between the lock mechanism 76 and the shaft or spindle 89 is disclosed in Figs. 25 and 26.

The lock mechanism 76 is provided with the cylinder 76A which is rotatably mounted and operated by the key lock mechanism, the cylinder 76A having a portion of its side wall cut away to form the shoulders or stops 76B for limiting the movement of the pin 89A which is mounted in the spindle 89 and adapted to turn therewith, the pin 89A allowing the spindle 89 to be rotated by the handle member 102 between the stops 76B without rotation of the key lock mechanism and at the same time allowing the key lock mechanism to be rotated without rotating the spindle 89 through a length of movement of the pins 89A between the stops 76B.

Also the dog member 87 will be in an unlocked position, as disclosed in Fig. 4, relative to said outer handle 79 and said roll-back 49, when said dog member 87 is operated to lower the talon 36 to a position where it may be engaged by the roll-back 49 to operatively connect the outer handle 79 with the plunger 28. Thus it will be noted that the plunger 28 together with the plate 38 may be retracted by the rod 112 together with

the handle member 120 operatively connected therewith, said handle member 120 being located on the inside of the door assembly 1, the above mentioned lost motion mechanism between the key lock mechanism 76 and the shaft 89 permitting the dog member 87 to be revolved from its position disclosed in Fig. 5 to that disclosed in Fig. 4 without movement of the key 75.

Also if the operator is on the interior of the body with which the door assembly A is assembled, the extension portion 133 may be operated by means of the handle member 102 and the shaft member 89 to the locking position as disclosed in Fig. 5 with the results as above described relative to the operation of the key 75 and the key lock mechanism 76. It will thus be noted that with the lock assembly B in a locked position as disclosed in Fig. 5, the lock mechanism B may be unlocked from the interior of the body of the vehicle by the leverage and handle mechanism or the lock mechanism B may be unlocked from the exterior of the body of the vehicle by the key and key lock mechanism.

Also it is to be especially noted that with the door and lock mechanisms in their closed and locked positions that it will be impossible for anyone such as undesired passengers, gunmen, etc., to jump on the running board of the vehicle and by grabbing the handle 78, to operate the lock mechanism B to an unlocked position or to break the handle or other operating parts of the door and lock mechanisms because continued operation of the handle member 78 merely revolves same with no further resultant operation of the lock mechanism B, thus providing safety characteristics which protect the operator and occupants of the body of the vehicle from undesired molestation and assault.

We claim:

1. In a lock mechanism for a door of a vehicle having a door post mechanism provided with a catch member together with a recess extending partially across the surface of the door post mechanism adjacent the door, the combination of a housing having a chamber therein and provided with a wall portion having an opening adjacent the catch member of the door post mechanism, an embossed portion on said housing and adapted to enter said recess of the door post mechanism, a guide member mounted in the chamber of said housing, a plunger member engaging said guide member and adapted to extend through said opening of said housing and engage said catch member of the door post mechanism, a plate member provided with a slot and a flange portion together with an indexing surface adapted to engage a flattened surface of a roll-back member to position the roll-back member in an indexed position, said plate member being secured to said plunger member, a member supported in said housing and extending through said slot of said plate member to support and retain said plate member, a dog member pivotally mounted on and adapted to be actuated to operate said plate and plunger members, a dog member rotatably mounted in said housing and provided with index portions, said dog member being provided with an extension portion adapted to engage said flange portion of said plate member, a connecting member pivotally connected with said dog members, an index member rigidly mounted in said housing and provided with grooves for engaging the index portions of said second dog member, a resilient member suitably mounted to exert a continual thrust on said plunger member to maintain it in

an extended position through said opening of said housing, a second resilient member continually exerting a thrust on said second dog member to cause its index portions to engage said index members, a shaft member suitably mounted to operate said second dog member to and from its engagement with the flange portion of said plate member, the operation of said second dog member causing said connecting member to move said first mentioned dog member to a position in which it is disconnected from a roll back member adapted for actuating said first mentioned dog member, a key lock mechanism suitably mounted and operatively connected with said shaft member, a handle member mounted on said shaft member, and located on the inside of the door of the vehicle, a second shaft member suitably mounted, a roll-back member mounted on said second shaft member and provided with a cam portion adapted to engage and operate said first mentioned dog member to move said plate and said plunger members, said cam member of said roll-back member being adapted for movement within said embossed portion of said housing, said roll-back member being provided with a plurality of flattened surfaces adapted to be engaged by said indexing surface of said plate member, a handle member mounted on said second shaft member and positioned on the outside of the door, and a third resilient member suitably mounted and engaging said flattened surfaces of said roll-back member.

2. In a lock mechanism for a door, the combination of a roll back member rotatably mounted, a handle operatively connected with said roll-back member and located on the outside of the door, said roll-back member being provided with a plurality of index surfaces arranged around its axis, a plunger mechanism slidably mounted to move solely in a longitudinal direction and adapted to engage an index surface of said roll-back member, resilient means adapted to maintain said plunger mechanism in engagement with said index surface of said roll-back member to position said roll-back member, a dog member pivotally mounted on said plunger mechanism and adapted to be engaged by said roll-back member to slidably operate said plunger mechanism against the thrust of said resilient means, a second dog member rotatably mounted and operatively connected with said first mentioned dog member to move said first mentioned dog member out of engagement with and to permit said roll-back member to be freely rotated by said handle member.

3. In a lock mechanism for a door, the combination of a housing provided with oppositely disposed walls each provided with a cylindrical opening together with a cylindrical recess thereadjacent, said cylindrical recesses having a larger diameter than said cylindrical openings, a roll-back member having a pair of cylindrical surfaces of different diameters at each of its ends and rotatably engaging said cylindrical recesses and openings of said housing, said roll-back member being provided with a plurality of index surfaces between said pair of cylindrical surfaces, a handle operatively connected with said roll-back member and located on the outside of the door, a plunger mechanism movably mounted and adapted to engage said index surfaces of said roll-back member, resilient means for actuating said plunger mechanism to engage said index surfaces of said roll-back member, a dog member pivotally mounted on said plunger mechanism and adapted

to be engaged by said roll-back member to movably operate said plunger mechanism, a second dog member rotatably mounted and operatively connected with said first-mentioned dog member to move said first mentioned dog member out of engagement with and to permit said roll-back member to be freely rotated by said handle.

4. In a lock mechanism, the combination of an index member fixedly mounted and provided with index portions, a dog member rotatably mounted and provided with index portions adapted to engage said index portions of said index member, resilient means for maintaining said dog member in engagement with said index member, a plunger mechanism, a second dog member pivotally mounted on said plunger mechanism, a link member pivotally connected with said first mentioned and said second dog members, a key lock mechanism operatively connected with said first mentioned dog member, and a roll-back member rotatably mounted and provided with a cam portion adapted to engage and operate said second dog member to operate said plunger mechanism, said second dog member being adapted to be operated by said key lock mechanism to a disengaged position relative to said roll-back member to permit said roll-back member to be freely rotated.

5. In a lock mechanism for a door, the combination of a roll back member rotatably mounted and provided with a plurality of flattened surfaces, a plunger mechanism movably mounted and provided with a portion adapted to engage one of said plurality of flattened surfaces of said roll back member, resilient means tending to urge said portion of said plunger mechanism to engage one of said plurality of flattened surfaces of said roll back member, a dog member rotatably mounted, means operatively connecting said dog member and said plunger mechanism and provided with a dog mechanism adapted to be engaged by said roll back member, said dog member being restrained to move in a sole plane due to its pivot mounting on said plunger member together with said means for guiding said plunger in a straight line, a resilient member suitably anchored and adapted to engage one of said flattened surfaces of said roll back member.

6. In a lock mechanism for a door, the combination of a roll back member rotatably mounted, a plunger member provided with a portion at its inner end having a lesser thickness than its outer end, a plate member secured to said lesser thickness of said plunger member and provided with a portion adapted to engage said roll back member, resilient means actuating said plate member to engage said roll back member, means for guiding said plunger and said plate members in a straight line, a dog member pivotally mounted on said plunger member adjacent its lesser thickness and adapted to be engaged by said roll back member, and a link member pivotally connected to said dog member and means for operating said link member to move said dog member.

7. In a lock mechanism for a door, the combination of a roll back member rotatably mounted, a plunger member provided with a pair of boss portions having a slot therebetween, one of said boss portions being extended beyond the other, means for preventing turning of said plunger member, a dog member pivotally mounted in said slot between said pair of boss portions and adapted to be engaged by said roll back member to move said plunger member, said dog member being restrained to move solely in one plane, a plate

75

- member suitably connected with said extended portion of said plunger member, resilient means actuating said plate member toward said roll back member, and means for operating said dog member to an inoperative position relative to said roll back member to permit free rotation of said roll back member, said means comprising a second dog member rotatively mounted.
8. In a lock mechanism for a door, the combination of a housing, a roll back member rotatably mounted in said housing and provided with index surfaces, a plunger member movably mounted in said housing and provided with an extension portion, a plate member secured to and extending over an end of said extension portion of said plunger member, said plate member being adapted to engage said index surfaces of said roll back member, a dog member pivotally mounted on said plunger member and adapted to be engaged solely by said sole roll back member to move said plunger member, resilient means suitably mounted on said housing and having a portion extending between said plate and a wall portion of said housing to engage and urge said plunger together with said plate member toward said sole roll back member, and means for operating said dog member to an inoperative position relative to said sole roll back member.
9. In a lock mechanism for a door, the combination of a roll back member provided with oppositely disposed index surfaces, a plunger mechanism movably mounted and provided with a portion adapted to engage one of said index surfaces of said roll back member, resilient means for urging said plunger mechanism toward said roll back member, a second resilient mechanism suitably anchored and engaging said roll back member on one of its index surfaces oppositely disposed to said index surface engaged by said portion of said plunger mechanism, a dog member pivotally mounted on said plunger mechanism and adapted to be engaged by said roll back member to move said plunger mechanism, and means for operating said dog member to an inoperative position relative to said roll back member.
10. In a lock mechanism for a door, the combination of a roll back member rotatably mounted, a plunger member movably mounted above said roll back member, a dog member pivotally mounted on said plunger member and provided with a pair of arm portions extending substantially at right angles with one another, one of said arm portions extending below said plunger member and having a surface adapted to be engaged by said roll back member, a plate secured to said plunger member and engaging said roll back member, said plate member having a cut out portion to provide operating space for said dog member, a resilient member for urging said plate member toward said roll back member, and means for operating said dog member to an inoperative position relative to said roll back member.
11. In a lock mechanism for a door, the combination of a roll back member rotatably mounted, a plunger mechanism movably mounted, a fixed member engaging said plunger mechanism at one of its sides to guide it in its movement, a dog member pivotally mounted on said plunger mechanism and adapted to be engaged by said roll back member, a second dog member rotatably mounted and adapted to engage said plunger mechanism, said second dog member being adapted to be held in a non-engaged position relative to said plunger mechanism, said dog member being provided with a surface adapted to guide said plunger mechanism, in cooperation with said fixed member, in its movement, resilient means opposing movement of said plunger mechanism, and a link member pivotally connected to said dog members.
12. In a lock mechanism for a door, the combination of a roll back member rotatably mounted, a plunger member movably mounted, a plate member secured to said plunger member and provided with an extension portion having a flanged end, resilient means opposing movement of said plunger and plate members, a dog member pivotally mounted on said plunger member and adapted to be engaged by said roll back member, a second dog member rotatably mounted and provided with an extension portion adapted to engage the flanged end of the extension portion of said plate member, and a link member pivotally connected to and between said dog members to move said first mentioned dog member out of engagement with said roll back member when said extension portion of said second dog member is engaging said flanged end of said plate member.
13. In a lock mechanism, the combination of an index member fixedly mounted and provided with index portions, a shaft member rotatably mounted, a dog member slidably mounted on said shaft member and provided with index portions adapted to engage the index portions of said index member, said dog member being adapted to be rotated by said shaft member, resilient means for maintaining said dog member in engagement with said index member, a plunger mechanism movably mounted, a roll back member rotatably mounted, a second dog member pivotally mounted on said plunger mechanism and adapted to be engaged by said roll back member, a link member pivotally connected to said second dog member, a stud member slidably mounted in said link member and connected with said first mentioned dog member, a resilient means opposing movement of said plunger mechanism, and a key lock mechanism operatively connected with said shaft member and adapted to operate said first mentioned dog member and said link member to move said second dog member to an inoperative position relative to said roll back member.
14. In a lock mechanism, the combination of an index member fixedly mounted and provided with index portions, a dog member rotatably mounted and provided with index portions adapted to engage said index portions of said index member, resilient means for maintaining said dog member in engagement with said index member, a shaft rotatably mounted and adapted to drive said dog member, said shaft extending through said index and said dog members, a plunger mechanism, a second dog member pivotally mounted on said plunger mechanism, a stud member mounted in said first mentioned dog member, a link member pivotally connected to said second dog member and provided with a bearing for slidably engaging said stud member, a key lock mechanism operatively connected with said shaft member, a roll back member rotatably mounted and provided with a cam portion adapted to engage and operate said second dog member to operate said plunger mechanism, said second dog member being adapted to be operated by said key lock mechanism to a disengaged position relative to said roll back member to permit said roll back member to be freely rotated, and

a handle member operatively connected with said shaft and adapted to operate said second dog member to its disengaged position relative to said roll back member, said handle member being oppositely disposed to said key lock mechanism relative to said first mentioned dog member.

- 5 15. In a lock mechanism, the combination of index means, a dog member slidably mounted and engaging said index means, resilient means for urging said dog member to engage said index means, a plunger mechanism, a second dog member pivotally mounted on said plunger mechanism, a resilient means opposing movement of said plunger mechanism, a roll back member 10 rotatably mounted and located between said dog members, a link member pivotally connected to said dog members and adapted to slidably support said first mentioned dog member in its slideable movement, and a key lock mechanism operatively connected with and adapted to rotate said first mentioned dog member to actuate said link member to move said second dog member to an inoperative position relative to said roll back member.
- 15 20 25 16. In a lock mechanism, the combination of a plunger mechanism slidably mounted and adapted for movement solely in a longitudinal direction, resilient means opposing movement of said plunger mechanism, roll back means for actuating said plunger mechanism, a link member, means for disconnecting said plunger mechanism from said roll back means to permit operation of said roll back means without effective movement of said plunger mechanism, said last mentioned means comprising a pair of dog members pivotally mounted and pivotally connected together by said link member. One of said dog members being adapted to be engaged by said roll back means, the other of said dog members being adapted to engage said plunger mechanism.

30 35 40 17. In a lock mechanism for a door of a vehicle body provided with a catch mechanism, the combination of a plunger mechanism adapted to engage said catch mechanism, a dog member

pivots mounted on said plunger mechanism, a roll-back member adapted to engage said dog member to operate said plunger mechanism, an outside handle member connected with said roll-back member, a key lock mechanism on the outside of said door, an inner handle member mounted in axial alignment with said key lock mechanism and connected therewith by lost motion mechanism, a second dog member adapted to be operated by said key lock mechanism, or said inner handle member, and a link member pivotally connected between said first mentioned and said second dog members, said link member being adapted to positively move said first mentioned dog member at all times when said second dog member is operated.

18. In a lock mechanism, the combination of an index member fixedly mounted and provided with index portions, a dog member rotatably mounted and provided with index portions 20 adapted to engage said index portions of said index member, resilient means for maintaining said dog member in engagement with said index member, a shaft rotatably mounted and adapted to rotate said dog member, said shaft extending 25 through said index and said dog members, a plunger mechanism, a second dog member pivotally mounted on said plunger mechanism, a stud member mounted in said first mentioned dog member, a link member pivotally connected to 30 said second dog member and provided with a bearing for slidably engaging said stud member, a key lock mechanism operatively connected with said shaft member, and a roll back member 35 rotatably mounted and provided with a cam portion adapted to engage and operate said second dog member to operate said plunger mechanism, said second dog member being adapted to be operated by said key lock mechanism to a disengaged position relative to said roll back member 40 to permit said roll back member to be freely rotated.
